UNITED STATES PATENT OFFICE

ERIK E. GUSTAVSON, OF MOLINE, ILLINOIS

GARAGE-DOOR MECHANISM

Application filed December 5, 1927. Serial No. 237,692.

My invention has reference to a garage door mechanism, and is similar in character to the mechanism for which I filed an application for letters patent of the United States 5 under date of June 28, 1926, Serial No. 118,999. In the present device it is the purpose to operate the doors of a garage entirely from the outside of the building, so that in case of entering or leaving the building it will not be necessary for the occupant of the vehicle to get out of same. This is of special advantage in case of a storm. The device is of comparatively simple form, and is effective in its operation.

15 In the drawings:—

Fig. 1 is a plan view of the apparatus, looking on the tops of a pair of doors in open position.

Fig. 2 is a side elevation of the operating 20 mechanism, in detail.

Fig. 3 is a section on the line 3—3 of Fig. 1.

Fig. 4 is a side elevation of the operating mechanism in position with the doors closed.

Fig. 5 is a similar view with the doors open.

25 Fig. 6 is a similar view with the spring 20 released, and the position of the parts changed to again close the doors.

Fig. 7 is an elevation with the parts shown in the reverse from that shown in Fig. 4.

30 The reference number 1 indicates a portion of the front wall of a garage or similar building, having an opening which is normally closed by a pair of doors 2 and 3, hinged at the sides of the opening, as at a, 35 so as to swing outwardly away from each other. At a central point above the door opening is secured a bracket 4, to which is pivoted a pair of folding braces consisting of relatively long arms 5 and short sections 6, the ends of which are pivoted to brackets 7, secured to the inner faces of the doors. A shaft 8 is rockingly mounted in the ends of supports 9 and 10 fixed to the building on the inside of the doors, at points

40 45 a little above the same, and secured to said shaft is a frame 11 the ends of which are pivotally connected by links 12 with lugs 13 on the arms 5, midway the ends thereof. Upon the shaft being rocked in one direction the doors are moved outwardly to a position

at right angles to the building, as shown in Fig. 3, and the rocking of the shaft in the opposite direction returns the doors to their former closed position.

The rocking of the shaft 8 is accomplished 55 by means of mechanism at one side of the doors, comprising a frame 15 supported on the inner face of the building, at about the height of the upper part of the doors. Vertically slideable in said frame is a draw-bar 16, and pivoted to the upper end of said draw-bar is an arm 17, having a pivotal connection with the frame 15, as at c. Pivoted to the arm 17 at d is a plunger 18, the lower end of which is slideable in an opening in the frame 15, and the upper end is slideable in a guide 19 on the support 10. On said bar is a compression spring 20, the force of which when compressed tends to force the plunger 18 and bar 16 upwardly. Fixed to the bar 16 60 is a cam-plate 21, above which is pivoted a plate 22, of less width than the cam 21. Fixed to the rock-shaft 8 above said plate is a cross-arm 23, from the ends of which are suspended a pair of arms 24 and 25, united by a coiled 65 spring 26, and adapted for alternative engagement with the cam 21.

When the bar 16 is drawn downwardly as in Fig. 4, with the doors closed, the arm 24 forces the plate 22 toward the other side of the bar, permitting the engagement of the end of the arm 24 with the cam-plate 21, and upon the bar being forced upwardly by the spring 20 the cross-arm 23 is rocked into the position shown in Fig. 5, also rocking the 70 shaft 8, and opening the doors. The rocking of the plate 22 above mentioned serves to bring the rear edge thereof into a position which is flush with that of the plate 21, so that as the arm 25 moves downwardly the 75 end thereof will slip over the joint between the plates 21 and 22, and pass a little ways below the same. When the bar 16 is moved downwardly again the plate 21 passes the end of the arm 25, and the action of the spring 80 85 90 95 26 causes said arm to force the plate 22 forwardly, providing lodgment for the end of the arm on the plate 22, as in Fig. 5. When the bar 16 moves upwardly again, impelled by the force of the spring 20, the cross-arm 100

- 23 is again rocked, bringing the doors back to a closed position. The movement of the plate 22 is limited by stops 27 and 28, which strike against the edges of the bar 16. In Fig. 5 the parts are shown with the spring 20 compressed, ready for the upward movement, and in Fig. 6 the spring is shown extended, and the parts in position at the end of the upward movement.
- 10 It will be observed that by the operations hereinbefore last described the arms 24 and 25 are alternately engaged by the plate 21, for the purpose of first opening the doors and then closing them. To carry out these operations the bar 16 is connected by a rod 30 with a bell-crank lever 31 fulcrumed on a bracket 32 secured to the wall 1. To the other end of said lever is attached a bar 33, projected outwardly through an opening in the wall of the building, and provided at its outer end with a rack 34 for operation by a segment gear pinion 35 on one end of a treadle 36, pivoted in bearings 37. The treadle is in the line of travel of the wheels on one side of an automobile passing into or out of the garage, said wheels, together with the weight of the vehicle, serving to turn the treadle downwardly and impart movement to the bar 33. When this movement is such as to turn the treadle 36 downwardly in the direction of the building the lever 31 is rocked in a direction to draw the bar 16 downwardly, storing power in the spring 20 and connecting said bar up with one or other of the arms 24 and 25. In case the treadle is moved in the other direction the rocking of the lever 31 has no effect upon the bar 16, a slack movement at the end of the rod 30 being permitted by a series of links therein at 42. After the wheel has passed over the treadle such treadle is returned to an elevated position by means of a coiled spring 39, connecting the upper end of a post 38 on one of the bearings 37 with a lug 40 on the pinion 35.
- 45 Assuming the vehicle to be in the garage, the doors 3 and 4 are first opened by hand, and the vehicle backed out in the usual manner, until the front wheel has passed over the treadle 36. The car is then moved toward the garage again, the downward movement of the treadle compressing the spring 20 and setting the parts for closing the doors. This operation is delayed, however, by devices hereinafter referred to, and actuated by 50 the vehicle when it passes over the treadle in moving outwardly again. When the vehicle approaches the doors from the outside one of the front wheels passes over the treadle, again setting the mechanism for operation to open the doors, and the vehicle is then backed up until the wheel operates the treadle again, which enables said mechanism to operate for opening the doors.
- The means for delaying the action of the 65 spring 20 consists in a latch 43, pivoted to

an arm 44 on the cross-arm 23, and slidable on a catch 45 on the plate 10. The latch is provided at each end with a shoulder for alternate engagement with the catch 45, by which means not only the latch is held from movement, but also the cross-arm 23 and door operating devices. In Fig. 4 the latch is shown in locked position with the doors closed, and interfering with the upward movement of the bar 16. In Fig. 5 the other 70 end of the latch is shown engaged with the catch 45, and the parts locked from movement with the doors in open position. The latch 43 is held yieldably in engagement with the catch by means of a coiled spring 46, connecting said latch with the frame 15. The support 10 is provided with a lug 47, (Fig. 2) on which is pivoted a trigger 48, engaging the lower face of the latch 43, connected by a cable 49 and link 50 with an arm 51 on the lever 31. When said lever is rocked in a direction to draw the bar 16 downwardly the cable is slack, with no effect on the latch mechanism, but upon the lever being rocked in the opposite direction the trigger 48 is actuated, raising the latch 43 and disengaging it from the catch. This movement is the result of the treadle being turned downwardly away from the building.

After entering the garage with a vehicle 95 the doors may be closed by hand, and the same method is employed for opening the same, before driving the vehicle out. In case the spring 20 is under tension when the doors are to be opened from the inside, such tension can be released by means of a hand-lever 52, pivoted to the bar 16, and engageable with the stops 27 and 28. If the parts are in the position shown in Fig. 4, the lever 52 is forced toward the building, moving the plate 22 in the same direction, and disengaging the arm 24. The latch 43 is then released by pulling the cord 49, and the doors are free to be moved outwardly. In the same manner if the doors are open, with the parts under tension as shown in Fig. 5, the plate 22 can be swung rearwardly by means of the hand-lever, disengaging the arm 25, and permitting the doors to be opened as soon as the latch 43 is released. The hand-lever is indicated only in Fig. 4.

What I claim, and desire to secure by Letters Patent, is:

1. In a garage door mechanism, a rock-shaft control device consisting of a draw-bar and tension devices for the operation thereof, double-acting cam devices on said bar, a cross-arm on said rock-shaft, and arms on the ends of said rock-shaft capable of alternative engagement with the cam devices to impart the movement of the draw-bar to said rock-shaft.

2. In a garage door mechanism, a rock-shaft control device consisting of a draw-bar and tension devices therefor, double acting

cam devices on said bar, a rock-shaft and cross-arm thereon, cam engaging devices on the ends of said cross-arm, for alternative engagement with said cam devices, a double acting latch mechanism for holding said rock-shaft at the end of each of its movements, means for actuating said draw-bar and tension devices to store power therein, and means for releasing said latch mechanism.

10 In testimony whereof I affix my signature.
ERIK E. GUSTAVSON.
